C. H. CLOWER.
BOAT PROPELLING MECHANISM.
APPLICATION FILED AUG. 8, 1914.

1,159,899.

Patented Nov. 9, 1915.

UNITED STATES PATENT OFFICE.

CHARLES H. CLOWER, OF PHILADELPHIA, PENNSYLVANIA.

BOAT-PROPELLING MECHANISM.

1,159,899.

Specification of Letters Patent.

Patented Nov. 9, 1915.

Application filed August 8, 1914. Serial No. 855,738.

To all whom it may concern:

Be it known that I, CHARLES H. CLOWER, a citizen of the United States, residing at Philadelphia, in the county of Philadelphia 5 and State of Pennsylvania, have invented certain new and useful Improvements in Boat-Propelling Mechanism, of which the following is a specification.

The object of my invention is to provide 10 a novel, simple and efficient propelling mechanism for water craft whereby an operator assuming a safe and easy position facing forward may operate same with a natural motion of the legs and arms and at 15 the same time govern the course of the craft and cause the progress of the craft to be uniform instead of spasmodic, by means of constant pressure on the main crank shaft.

With this object in view, my invented 20 mechanism consists of the elements and the combinations of them hereinafter fully described and particularly claimed.

In the accompanying drawings, illustrating 25 my invention: Figure 1, is a plan of the rear portion of a boat provided with my improved propelling mechanism, omitting the seat. Fig. 2, is a longitudinal section through the body of the boat, showing the mechanism in elevation. Fig. 3, is a trans- 30 verse section through the body of the boat, showing the mechanism in elevation.

Referring to the drawings, 2 designates 35 the body of the boat which may be of any suitable design. Within the rearward portion of the boat is a transversely-extending shaft 3, constituting the main driving shaft 3 of the propelling mechanism. This shaft 3 is mounted to rotate in suitable bearings 4 mounted in the boat and it carries a 40 sprocket wheel 5 which is connected by a chain 6 to a sprocket wheel 7 on a short shaft 8 mounted in a bearing on a bracket 9 within the boat. The shaft 8 is provided with a bevel gear wheel 10 in mesh with a 45 similar wheel 11 on a shaft 12 which extends longitudinally of the boat and rearwardly of the main shaft 3. The shaft 12 extends through the wall of the boat and is mounted to turn in a bearing therein and 50 in a bearing on the bracket 9; and the rear end of the shaft 12 carries the propeller 13.

By the construction thus far described, 55 it will be readily understood that when the shaft 3 is rotated, the propeller 13 will be actuated.

Any suitable gearing may be employed

between the shafts 3 and 12 without departing from my invention.

I shall now describe the mechanism whereby the shaft 3 may be rotated by the 60 hand and foot power of a person seated within the boat.

The shaft 3 has four cranks 14, 15, 16, and 17 formed thereon, as shown. The cranks 14 and 15 are connected by forwardly-extending rods 18 and 19 to the lower ends of rocking levers 20 and 21 which are fulcrumed on brackets 22 and 23, respectively, secured to the body of the boat. The levers 20 and 21 are fulcrumed midway of their 70 ends and their upper ends are connected to the forward ends of rods 24 and 25, respectively. The rear ends of the rods 24 and 25 are connected to a pair of hand levers 26 and 27, respectively, located adjacent the 75 two side walls of the boat and adjacent the main driving shaft 3. The lower ends of the hand levers 26 and 27 are fulcrumed on brackets 28 and 29 secured to the body of the boat. The hand levers 26 and 27 are 80 located forwardly of and adjacent the two ends of a suitable seat 30 which extends transversely between the two side walls of the boat and is located above the main driving shaft 3, so that a person sitting on the 85 seat 30 between the two hand levers 26 and 27 may grasp the upper ends thereof, and, by moving them forward and back, rotate the main shaft 3 by the connections just described, and as will be hereinafter explained.

The cranks 16 and 17 are connected to the rear ends of rods 31 and 32, respectively, which extend forwardly from the cranks and have suitable foot pedals 33 and 34, re- 95 spectively formed on the forward ends thereof. The forward ends of the rods 31 and 32 are connected to cranks 35 and 36 formed on two rocking shafts 37 and 38, respectively, which are mounted in alignment with each other in the brackets 22 and 23 and in a central bracket 39. The foot pedals 33 and 34 are located a suitable distance in advance of the seat 30, so that the person sitting upon the seat and operating 100 the hand levers 26 and 27 may also move the foot pedals forward and back and cause them, through the connections just described, to assist in rotating the shaft 3.

The hand levers, foot pedals and cranks 110 on the main shaft are so located with respect to each other, that when a person sits

upon the seat 30 and operates the mechanism, the right hand and right foot will go forward while the left hand and left foot are being drawn back, and the converse; and that rearward pressure on the hand levers and forward pressure on the foot pedals will turn the shaft 3 to drive the boat forwardly. Thus the pressure of the right hand and left foot will alternate with the pressure of the left hand and right foot in driving the propeller.

To steer the boat while being propelled, I provide the following: Mounted in a bracket 40 secured to the body of the boat 2, is a short vertical shaft 41 having a hand wheel 42 on the upper end thereof which is located directly in front of the seat 30. The shaft 41 carries a drum 43 to which are secured the forward ends of a pair of ropes 44. The ropes 44 extend one from one side and one from the other side of the drum 43 and have their rearward ends connected to the ends of a transverse bar 45 on the upper end of the pivot bar 46 of a rudder 47, the pivot bar 46 being mounted to turn in suitable brackets on the rear end of the boat. By turning the wheel 42, the rudder 47 may be set to control the course of the boat, and this may be done at different times by the person operating the propelling mechanism removing a hand from one of the hand levers a short time to operate the wheel 42 each time it is desired to change the course.

I claim:

1. The combination of a boat, a rotatable shaft journaled in bearings therein and having four cranks formed thereon, a propeller, gearing between the propeller and the shaft, two rocking cranks having foot pedals and rods connecting them to two cranks of said rotatable shaft, two rocking levers, rods connecting said rocking levers to two cranks of said rotatable shaft, two hand levers and rods connecting said rocking levers and said hand levers.

2. The combination of a boat, a rotatable shaft journaled in bearings therein and having a crank formed thereon, a propeller,

gearing between the propeller and the shaft, a rocking shaft having a crank formed thereon, and a rod having one end connected to the crank on the rotatable shaft and having the other end provided with a foot pedal and connected to the crank on the rocking shaft.

3. The combination of a boat, a rotatable shaft journaled in bearings therein and having two cranks formed thereon, a propeller, gearing between the propeller and the shaft, a hand lever fulcrumed in the boat, a rocking lever fulcrumed in the boat, a rod connecting the levers, a rod connecting the rocking lever to one crank on the rotatable shaft, a rocking shaft having a crank formed thereon, and a rod having one end connected to one crank on the rotatable shaft and having the other end provided with a foot pedal and connected to the crank on the rocking shaft.

4. The combination of a boat, a rotatable shaft journaled in bearings therein and having two cranks formed thereon, a shaft extending rearwardly from the first named shaft through the wall of the boat and having a propeller on the rear end thereof, gearing between said shafts, a hand lever fulcrumed in the boat adjacent said rotatable shaft and having a rod connected thereto and extending forwardly therefrom, a rocking lever fulcrumed in the boat forwardly of the hand lever and connected to said rod, a rod connecting said rocking lever to one crank on said rotatable shaft, a rocking shaft forwardly of the hand lever and having a crank formed thereon, and a rod having its rear end connected to one crank on said rotatable shaft and having its forward end provided with a foot pedal and connected to the crank on said rocking shaft.

In testimony whereof I affix my signature in presence of two witnesses.

CHARLES H. CLOWER.
